Patented Mar. 26, 1918.

UNITED STATES PATENT OFFICE.

JUDSON L. MCKELLAR, OF BROOKLYN, NEW YORK, ASSIGNOR TO GASAU-THOMPSON COMPANY, INC., OF BROOKLYN, NEW YORK, A CORPORATION OF NEW YORK.

BEDSTEAD.

1,260,417.

Specification of Letters Patent. Patented Mar. 26, 1918.

Application filed May 27, 1915. Serial No. 30,712.

To all whom it may concern:

Be it known that I, JUDSON L. MCKELLAR, a citizen of the United States, and a resident of Brooklyn, in the county of Kings and State of New York, have invented certain new and useful Improvements in Bedsteads, of which the following is a specification.

The invention pertains more particularly to a novel spring composed of separate units adapted to be applied to bedsteads whether of the metal variety or made of wood. The spring units of my invention when applied to metal bedsteads will be suspended upon the side rails thereof by means of suitable arms carried by said units, and when said spring units are applied to wooden bedsteads they will be placed directly upon the slats thereof. The spring units of my invention will vary in size in accordance with the size of the bedstead frame to which they may be applied, and ordinarily it will be found convenient to have said units of such dimensions that two or three thereof will be sufficient for a bedstead of the usual length. By making the spring in units or sections, a very strong and durable bed spring structure may be formed, and in addition the separate units by being of durable character may be handled, shipped and moved about with convenience and without special danger of becoming injured. The spring units of my invention will be detachably applied to bedsteads, and when so applied will receive the mattress in the usual way.

The invention will be fully understood from the detailed description hereinafter presented, reference being had to the accompanying drawings, in which:

Figure 1 is a top view of a portion of a bedstead equipped with spring units embodying my invention;

Fig. 2 is a sectional view on a larger scale and partly broken away, through the same taken on the dotted line 2-2 of Fig. 1, and

Fig. 3 is a side elevation of a small portion of the bedstead frame and of one of the spring units of my invention.

In the drawings, 10 designates the side rails of a metal bedstead of usual character, and 11 one of the end frames thereof and to which the side rails are connected in the customary manner.

The spring units of my invention are

numbered, as a whole, 12 and are detachably supported upon the side rails 10. Each unit 12 is composed of an upper wire structure comprising a rectangular frame 13 of reasonably heavy wire and longitudinal and transverse wires 14 running at right angles to each other and connected at their ends to the frame 13 and affording a support for the usual mattress, not shown. The crossed wires 14 are connected with the upper ends of a series of coiled wire springs 15 of usual character and these springs are secured at their lower ends to a lower frame structure constituting the base of the unit and formed of angle side bars 16, angle end bars 17 and transverse bars 18 which are flat and bent angularly at their ends and riveted to the side bars 16. The bars 16, 17 are riveted together at their ends and the bars 18 are connected together in pairs by short longitudinal bars 19 which present a flat upper surface, as shown in Fig. 2, and are bent downwardly at their ends and riveted to the bars 18. The lower structure comprising the bars 16, 17, 18 and 19 present a rigid frame and this frame is further strengthened by a central longitudinal wire rod 20 which connects the end bars 17 and extends through the bars 18. The coiled springs 15 are connected at their lower ends to the transverse bars 18, said bars 18 being slit to receive the lower coil of said springs.

Upon the short longitudinal bars 19 are pivotally mounted the bracket arms 21, there being two of these bracket arms at each side of the lower frame structure of the unit. The bracket arms 21 are slotted at their inner ends, as at 22, so that they may be adjusted laterally on the rivets 23 securing them to the bars 19, this lateral adjustment being desirable in adapting the units to beds varying in width. The outer ends of the arms 21 extend upwardly, outwardly and downwardly to form box loops or hooks 24 adapted to engage the upper portions of the side rails 10 of the bedstead frame and thereby suspend the unit in said frame. The angle side bars 16 of the lower structure of the unit have secured to them metal plates 25 which extend upwardly and are formed with longitudinally extending members 26 between which and the bars 16, the bracket arms 21, when in operative position, extend, said members 26 serving to hold the outer portions of the arms 21 close down upon the 110

side bars 16 and prevent said arms from being bent upwardly due to any pressure which might be placed upon the bed. The rivets 23 alone would hardly be sufficient to sustain the arms 21 in the actual use of the bed unit, and hence I have provided the plates 25 which serve to hold the arms 21 rigidly down upon or close to the side bars 16 and resist any tendency of the arms 21 to bend upwardly at their outer portions. The bracket arms 21 are laterally adjustable as aforesaid so that their hook members 24 may assuredly engage the side rails 10 even though there may be some slight variations in the width of the bedstead frames to which the units may be applied. The rivets 23 hold the bracket arms 21 with sufficient freedom to permit of the lateral adjustment of said arms and also to allow said arms to be turned inwardly in line with the longitudinal bars 19 below the upper structure of the unit. When the units are kept in stock or are to be shipped, it is desirable that the bracket arms 21 be turned inwardly out of the way. The overhanging members 26 of the plates 25 permit the bracket arms 21 to be turned under them and from under them as will be readily understood on reference to Figs. 2 and 3. It is also desirable that the bracket arms 21 be capable of being turned inwardly out of the way when the units are to be used upon a wooden bed, because in that use of the units the lower frame structure thereof may be set directly upon the usual bed slats, and since when the units are supported on the bed slats it is not necessary that the bracket arms be

made use of. The units will customarily be employed on metal bedstead frames, but may also be conveniently employed on wooden bedsteads.

What I claim as my invention and desire to secure by Letters Patent, is:

A bed-spring in transverse units to be removably applied to a bedstead, each unit comprising an upper structure adapted to receive a mattress, a lower structure adapted to be supported by a bedstead, a series of coiled springs interposed between said upper and lower structures, and a plurality of bracket arms on each side of the unit adapted to be hooked upon the side rails of the bedstead, said lower structure comprising a rectangular frame of side and end bars, transverse bars arranged on edge and at their ends secured to said side bars and longitudinal bars arranged flatwise between and at their ends secured to said transverse bars, said bracket arms having hook-shaped outer ends and at their inner ends being pivotally secured on said longitudinal bars and also slotted to admit of longitudinal sliding movement on said bars, and said side bars having secured thereto plates below which said bracket arms may be turned and which serve to aid in sustaining said arms when the same are in use.

Signed at New York, in the county of New York and State of New York, this 4th day of May A. D. 1915:

JUDSON L. MCKELLAR.
